UNITED STATES PATENT OFFICE.

WILLIAM FRANCIS ALTENBAUGH, OF TIFFIN, OHIO, ASSIGNOR, BY DIRECT AND MESNE ASSIGNMENTS, TO THE UNITED STATES GLASS COMPANY, OF PITTSBURG, PENNSYLVANIA.

MACHINE FOR FINISHING GLASSWARE.

SPECIFICATION forming part of Letters Patent No. 599,822, dated March 1, 1898.

Application filed April 5, 1897. Serial No. 630,783. (No model.)

To all whom it may concern:

Be it known that I, WILLIAM FRANCIS ALTENBAUGH, a citizen of the United States, residing at Tiffin, in the county of Seneca and 5 State of Ohio, have invented a new and useful Improvement in Machines for Finishing Glassware, of which the following is a specification.

In the operation of finishing glassware 10 which requires reheating, such as tumblers, I use as tools a plug and a cup, the latter receiving and conforming to the shape of the tumbler, and with these tools used in successive steps the article is manipulated upon and 15 with correlated parts supported in a frame having a work-table. Of these tools the plug is used with a fixed guide erected upon the table, by which the tumbler is centered in placing it by a punty bottom side up upon 20 the plug. The cup is mounted upon a vertical shaft, and the tumbler is transferred by the plug within the cup, wherein it is given perfect shape. I make the inner walls of the cup of polished cast-iron to be better adapted 25 for such a finishing operation than the methods of rotating the glass in contact with a stationary pasted or wooden cup. In these particulars my improvements consist in certain novel parts and combinations of parts hereinafter specifically set forth in the claims 30 concluding this specification.

The following description, read in connection 35 with the drawings, will enable any one skilled in the art to which my invention relates to understand its nature and to practice it in the form in which I prefer to employ it; but it will be understood that my invention is not limited to the precise form herein illustrated, as various modifications may be made 40 without exceeding the scope of the claims.

It will be understood that the work of this machine is the finishing of tumblers and other articles after they have been reheated in what is known as a "glory-hole furnace" to reduce 45 the article to a symmetrical form. In this reheating operation the tumbler becomes more or less out of shape, and my machine is rapidly and conveniently to give form and finish to the tumbler.

50 Referring to the drawings, Figure 1 is a ver-

tical section of my improved machine, a reheated tumbler being shown in position upon the plug, another tumbler having been transferred from the plug to the cup. Fig. 2 is a horizontal section taken beneath the table, 55 showing the provisions for swinging the cup-supporting shaft to control its rotation and for lifting the tumbler from the cup. Fig. 3 is a vertical transverse section of the machine. Figs. 4 and 5 are enlarged side views 60 of the swing-frame and of its cup-supporting shaft in different positions. Fig. 6 is a vertical section of the cup-supporting shaft, and Fig. 7 shows the tongs for handling the tumblers. 65

In working with the machine the tumbler is taken from the mold by a punty 1 and carried to the reheating-furnace, heated and placed upon the plug 2, which is first placed upon the table and centered by a table-pin 3 70 in vertical alignment with guides 4 in a vertical frame, within which guides the staff of the punty is placed to guide the tumbler vertically upon the plug, in which position the tumbler is knocked off the punty. The plug 75 has a stem 5 with an enlarged end on which the tumbler rests in an inverted position, and the base of the plug is provided with a semi-circular curb or flange 6, within which the open end of the tumbler fits and whereby it 80 is held central upon the plug and is allowed to be readily transferred from it. By means of a handle 7 the plug is removed and the tumbler thereon transferred into the cup by turning it off of the plug with its open end up. 85 The plug is returned to its position to receive another tumbler from the punty to be transferred in the same way. The cup is of metal, preferably of cast-iron, smooth polished on its inner walls to prevent the tumbler sticking thereto. It is seated upon the shaft 9, by 90 which it is rotated, and in its rotation its shaping may be aided by a buffer of wood or other suitable material.

The cup-supporting shaft is mounted by a 95 suitable step 10 and bearings 11 in a vertical hanger 12, hung by a horizontal arm 13, pivotally connected to the frame 14, preferably at one end thereof and beneath the table 15, so that the hanger is free to swing laterally with- 100

in certain limits with its shaft, there being an opening 16 in the table through which the shaft passes to carry the cup above it. Above the hanger and preferably below the table the 5 shaft has a pulley 17, from which a belt 18 leads to a power-driven pulley for rotating the cup. The belt from the shaft-pulley passes under idle-pulleys 19, and the belt is made taut or slack to control the rotation of 10 the cup by means which I will presently describe.

The cup-supporting shaft is hollow, and within it is fitted a rod 20, having a disk 21, the normal position of which is just below the 15 cup-seat 22, so that when the rod 20 is lifted the disk 21 will lift the tumbler out of and above the cup, as shown in Fig. 5. This lifting of the tumbler is effected by the cord 23, attached to the lower end of the lifting-rod, 20 there being a vertical slot 24 in the shaft for such attachment, said cord passing over a pulley 25 at the top of the hanger and connecting a lifting-arm 26, pivotally connected to the table. This lifting device maintains its 25 normal position by gravity, and its cord connection may have a guide-rod 27 to prevent the lifter from binding in its movement in the tubular shaft. Referring to Figs. 5 and 6, it will be seen that the lifting-rod has a pin 36 30 on its lower end which projects through the slot in the shaft and that the lifting-cord connects this pin by an arm or ring 37, fixed to said pin, so that the pulling up of the cord thereby raises the lifting-rod. At its upper 35 end the shaft-hanger has a horizontal stirrup or forked arm 28, situated at or near its swing side, by which the hanger is swung toward and from the front of the machine to tighten and slack the shaft-pulley-propelling belt to 40 control the rotation of the cup.

The normal position of the hanger is maintained at the limit of its backward movement by a brake 29 under the pulling action of the shaft-propelling belt, and in this position the 45 pulley-belt is slack, so that the cup does not rotate. To render the belt taut for rotating the cup, the shaft-supporting hanger is pulled toward the front and away from the brake by the knee of the finisher.

To lift the tumbler from the cup, the lifting cord-connected arm 26 is moved away from the hanger by the knee of the finisher. 50 In working with the machine the operator sits facing the cup with his left knee in the hanger-stirrup and his right knee against the pivoted arm, which connects the tumbler-lifter. The tumbler having been knocked off the punty on the plug, the tumbler is transferred thereby into the cup. The finisher 55 then by moving his left knee to the left pulls the hanger toward the front, thereby tightening the pulley-belt and rapidly rotating the cup, which is fixed upon the shaft, and during such rotation the tumbler is given the 60 exact form of the cup.

By my invention all defacement or marring of the surface of the glass article is prevented

and the operation of shaping the glass is performed cheaply and rapidly. In this operation the tumbler cools sufficient to allow it to 70 be removed, which is done by the operator changing the pressure of his left knee in the stirrup from a forward direction to a rearward direction, thereby forcing a hub 30 on the cup-carrying shaft against the suitable 75 brake 29, fixed upon the table, thereby quickly stopping the rotation of the cup. Then moving his right knee to the right against the pivoted arm forces it outward, thereby pulling the cord 23 and raising its connected 80 tumbler-lifter, carrying the tumbler above the cup and holding it in that position. The finisher then applying a suitable fork (shown in Fig. 7) to the bottom of the tumbler removes it from the lifting-disk 21 and places 85 it in a seat 31 on a shelf 32, fixed to and projecting from the end of the table. This shelf is provided with one or more rows of seats, 90 within which the tumblers are collected from the cup, and intersecting these rows of seats 95 there is a surface groove 33, which is for receiving one of the fork-tines in applying it beneath the tumblers to remove them to the tempering-oven.

The knee tumbler-lifting device leaves the 95 finisher free to use his hands in the work upon the tumbler, facilitates the work, and enables it to be done with a finishing-cup fixed to its rotating shaft.

The frame may have rolling supports for 100 convenience in using it.

I prefer to attach the lifting-cord pulley and the stirrup to the same arm and connect the latter to the shaft-hanger; but said pulley may be suspended from the table. 105

It will be understood that the cup is open at both ends and is fixed upon an interior shoulder 34 in the cup-seat, that the tumbler rests upon the walls of the cup, that the normal position of the lifting-disk is below or level 110 with this seat-shoulder, so that in raising the disk it lifts the tumbler from the cup-walls, and that the lifting movement carries the tumbler above the cup to allow it to be removed therefrom without disturbing the position of 115 the cup upon the shaft which carries and rotates it. As seen in Figs. 1 and 6, the seat for the cup is a ring circumferentially screw-threaded and engages the interior-threaded hub fixed on the end of the shaft, whereby 120 the cup-seat may be adjusted vertically to raise or to lower it within the annular space at the top face of the hub to allow for slight variations in the size of the tumblers. In this adjustment the tumbler may go slightly 125 through the cup and rest upon the lifting-disk, so that each tumbler is thereby exactly formed the size of the cup. As the cup-seat would be liable to turn, I provide for fastening the cup-seat when set by its flange to the 130 shaft-hub by means of a pin 35, which passes through the seat-flange into one of a series of holes in the rim of the hub, as seen in Fig. 6.

While I prefer to make the cup of cast-iron,

polished on its finishing-walls, it may be made of other metals or of similar substances that will furnish hard polished walls on which the tumbler is finished and that will resist the effects of the heat.

5 I claim as my improvement—

1. In a machine for finishing glassware, the combination with a fixed table and a brake device fixed thereon, a shaft having a finishing-cup, above the table, and a belt-driven pulley, a swing-hanger for said shaft, a stirrup or arm on said hanger whereby said hanger may be swung to cause the cup-supporting shaft to engage said brake and means for rotating said shaft.

10 2. In a machine for finishing glassware the combination with a fixed table having an opening 16 and a fixed brake device 29, of a hollow shaft passing through said table-opening and having a hub 30 and a slot 24 below said hub, a pivotally-mounted hanger within which said shaft is mounted, an annular seat on said shaft, a finishing-cup on said shaft-seat, a stirrup or arm on said hanger, a rod 25 within said shaft having a disk on its upper end and a pin on its lower end projecting through said slot, a cord connecting said pin, and a pivoted arm connecting said cord and means for rotating said shaft, whereby the 30 finisher with his knee engaging the stirrup, swings the cup-carrying shaft in engagement with the brake to stop the rotation of said shaft and with his knee engaging the said pivoted arm lifts the shaft-rod to effect the removal of the finished article from the cup.

35 3. In a machine for finishing glassware, a cup for containing the article to be finished, fixed upon the end of a shaft and rotated by it, the said shaft being mounted in a swing-hanger, and having a belt-driven pulley by 40 which it is rotated, means for controlling the swing movement of said shaft-hanger and means for removing the tumbler operated upon within said cup.

45 4. In a machine for finishing glassware and in combination, a cup for containing the article to be finished, a hollow shaft on which said cup is fixed and rotated by it, a swing-hanger for said shaft, a fixed brake adapted 50 to contact with said cup when the shaft is not positively driven and a lifting device for the tumbler operating within the bottom of the cup and means for swinging the hanger for the purpose stated.

55 5. In a machine for finishing glassware and in combination with a cup for containing the article to be finished, a device for supporting and rotating said cup consisting of a shaft carrying said cup and having a pulley, a 60 swing-hanger for said shaft, a driving-belt running on a pulley on said shaft, a fixed brake against which said shaft is swung and a stirrup on said swing-hanger, whereby to receive the knee of the finisher for controlling the rotation of the cup.

6. In a machine for finishing glassware the combination with a cup for containing the article to be finished, a shaft carrying said cup, a tumbler-lifting device within the bottom of said cup, and means connecting said lifter with a device, actuated by the knee of the finisher for raising and holding up said lifter to raise the tumbler out of and above the cup.

7. In a machine for finishing glassware, a work-table, a plug and a rotating cup thereon for containing the article to be finished, and a shelf at the end of said table provided with seats for the article in rows and grooves intersecting said seats whereon the tumblers are gathered for removal for subsequent tempering operation.

8. In a glass-finishing machine, a cup for containing the article to be finished, a shaft supporting said cup, having a vertical slot, means for controlling the rotation of the shaft, a device within said shaft for lifting the finished tumbler therefrom, and means for operating said lifting device consisting of the cord connecting the pin on the lower end of said rod, said pin movable in said slot, the cord and a pivoted arm 26 connecting said cord, in the way described.

9. In a machine for finishing glassware, a hollow shaft having a fixed cup for containing the article to be finished, a slot communicating with said hollow, a rod within the shaft having a disk above said shaft, and a laterally-projecting pin, a cord attached at one end to said rod and a movable arm having a fixed relation to the machine and connecting said cord, whereby the movement of said arm is caused to lift the tumbler from the cup, and means for rotating said shaft.

10. In a machine for finishing glassware, the combination of a shaft having a ring-seat fixed thereon, a ring-seat vertically adjustable within the shaft-seat, a finishing-cup within said adjustable seat, means for rotating said shaft and means within said shaft for lifting the finished article from its containing-cup.

11. In a machine for finishing glassware, the combination of a shaft having a ring-seat fixed thereon provided with an interior thread, a ring-seat having a screw for adjustably engaging said shaft ring-seat, a finishing-cup within said adjustable ring-seat and means for rotating said shaft, and means within said shaft for lifting said cup, whereby the said cup-containing seat is rendered adjustable in relation to said lifting device.

In testimony whereof I have hereunto signed this specification in the presence of witnesses.

WILLIAM FRANCIS ALLENBAUGH.
